(57) **CLAIM**

The ornamental design for a carcass polishing whip, as shown and described.

DESCRIPTION

FIG. 1 of the drawings is a top plan view of the carcass polishing whip, showing, in particular the ornamental design thereof;

FIG. 2 of the drawings is a bottom plan view thereof;

FIG. 3 of the drawings is a front elevational view thereof;

FIG. 4 of the drawings is a rear elevational view thereof;

FIG. 5 of the drawings is a left side elevational view thereof; and,

FIG. 6 of the drawings is a right side elevational view thereof.

The inner circular portions in FIGS. 3 and 4 shown in broken lines are for illustrative purposes only and form no part of the claimed design.
